UNITED STATES PATENT OFFICE.

DAVID HILL, OF WEST BARRINGTON, RHODE ISLAND.

MOTOR-VEHICLE HEATER.

Application filed July 16, 1926. Serial No. 122,836.

This invention relates to an improved heating system for the body of a motor vehicle; and has for its object to provide a simple and effective device to be connected 5 to the exhaust conduit of a motor and arranged to draw cold air from the body of the vehicle to be heated and returned thereto. The heating system is so inclosed as to exclude all exhaust gases and prevent 10 them from being passed thereby into the body of the vehicle.

A further object of this invention is to provide a heat-conducting pipe arranged to communicate with the body of the vehicle, 15 one end of the pipe being located adjacent the exhaust conduit of the motor, and to mount a heat-directing element on the exhaust conduit to assist in heating the air and in inducing a circulation through the 20 system, a portion of the conductor pipe being enclosed in a chamber which is also connected to the body of the car to obtain cold air to be heated by circulating about the exhaust conduit to subsequently flow 25 back into the car through the heat-conducting pipe.

With these and other objects in view, the invention consists in certain novel features of construction, as will be more fully described, and particularly pointed out in the appended claims.

In the accompanying drawings:

Figure 1 is a fragmental section of a motor vehicle showing a portion of the body in 35 section and a portion of the engine with my improved heating system applied to the exhaust conduit thereof.

Figure 2 is an enlarged sectional view of the heating system shown in Figure 1.

Figure 3 is a detail in section showing the heat-directing element which is adapted to 40 be clamped to the exhaust conduit.

Figure 4 is a modification showing the heater as connected to the floor of a car to 45 discharge its heat into the body at a point in front of the front seat and having a cold air supply pipe communicating with the body at a point to the rear of the front seat thus causing the heated air to circulate to this 50 point.

Figure 5 is a perspective view of the construction shown in Figure 4.

Figure 6 shows the cold air chamber as 55 formed in two parts and adapted to be clamped about the exhaust conduit.

It is found in the heating of the body

portion of an automobile that where the cold air is drawn from the outside at a point about the exhaust pipe beneath the body, that a back draft is often caused which 60 draws some of the exhaust gases discharged from the exhaust pipe back into the body, also in traffic the gases from other adjacent cars is conducted into the body of the car, which is very objectionable and injurious 65 and renders such a heating system unpopular and sometimes dangerous. To obviate this difficulty, and prevent these exhaust outside gases from entering the heating system, I have provided a system closed 70 to the outside air, whereby the cold air to be heated is drawn from the interior of the vehicle body into a chamber formed about the exhaust conduit where this air is heated and then directed back through a 75 conductor pipe into the body of the vehicle thus creating a continuous circulation which effectually excludes the exhaust gases; and the following is a detailed description of 80 the present embodiment of my invention 85 showing means by which these advantageous results may be obtained:—

With reference to the drawings, 10 designates the motor and 11 the body of the vehicle. An exhaust conduit 12 leading from the motor is shown extending down beneath the body of the car towards the rear thereof. As is well known, the exhaust gases from the motor heat this conduit to a high temperature and in order to conduct 90 some of this heat into the body of the vehicle in a simple and practical way, I have provided an outer chamber 13, which is preferably formed in two parts, the lower part 14 being arranged to telescope into the upper 95 part 15 and each part being provided with a flanged portion 16 which is arranged to embrace the conduit 12 and be secured in position thereon by a clamp collar 17 which binds these upper and lower sections firmly 100 onto the conduit.

In some instances, the chamber 13 is supplied with cold air through the pipe 18 which is arranged to communicate with the inside of the vehicle body 11, preferably 105 through the dash board thereof, for the purpose of drawing the air therefrom, and as illustrated in Figures 1 and 2 a return or hot air conducting pipe 19 is positioned to have an open end 20 in proximity to the motor exhaust conduit 12, its opposite end 21 communicating with the interior of the 110

body of the vehicle through the dash board at a point above the cold air intake.

In order to cause a proper circulation of hot air through the conductor pipe, I have provided a collar member 22 which is shown in Figure 3 as being split and adapted to be clamped about the exhaust conduit 12 by bolts 23 and this collar is provided with a protuberance 24 which extends into the open end of the conductor pipe 19, whereby this protuberance when heated serves to create a draft and induce a current of heated air up through the hot-air conducting pipe into the body of the vehicle, which air is supplied to the outer chamber 13 by the pipe 18 from the body of the vehicle, thus providing a circulating heating system closed to the outside air which is very effective in its operation and at the same time effectually excludes the exterior exhaust gases which are being discharged both from its own exhaust pipe as well as those of other adjacent vehicles.

In some instances, it is found of advantage to mount the heating system at a point adjacent the engine and forward of the dash board of the body portion, while in other instances particularly where the car is of the double seated type, it is of advantage to mount the heating system below the floor just forward of the front seat of the car, in which case the cold air chamber may be a straight pipe 24 connected to the under side of the floor 25 through a hole therein just forward of the front seat 26 and a heated air conducting pipe 28 may be positioned within the outer pipe 24 to discharge the heated air at this point into the car, and in order to cause a proper circulation at a point back of the front seat, I have provided a cold air supply pipe 27 which is connected

through the floor just back of this front seat 26, which serves to draw the cold air from this point and induce a circulation of hot air to this portion of the body, which has heretofore been found difficult to heat.

My improved heating system is very simple and practical in construction and is effective in its operation and by its use the body of the car can be comfortably heated and the exhaust gases excluded therefrom.

I claim:

1. A heating system for a motor vehicle having a body and an exhaust conduit, comprising a conductor for heated air communicating at its upper end with the vehicle body, its lower end being open and extending in proximity to said exhaust conduit, an air heating and directing element mounted in contact with said conduit and having an upwardly extending tapering boss or protuberance extending into the open end of said conductor, and an outer casing about the open end of said conductor having an air intake opening. 65

2. A heating system for a motor vehicle having a body and an exhaust conduit, comprising a separable casing embracing said conduit forming an air chamber about the same and having an air intake opening at a point above the conduit, a conductor for heated air communicating at its upper end with the vehicle body, its lower end being open and extending into said chamber and into proximity to said exhaust conduit, and an air heating and directing element mounted on said conduit and having a tapered boss or protuberance extending into said open lower end. 75

In testimony whereof I affix my signature.

DAVID HILL.
